EDWARD J. ABBOTT, OF WILTON, NEW HAMPSHIRE.

WINDING AND UNWINDING YARNS OR THREADS.

Application filed May 18, 1923. Serial No. 639,830.

This invention relates to a method of winding textile yarns and apparatus adapted to wind and unwind yarns according to the method.

- In recent practice, particularly in the worsted yarn trade, it is common to wind a number, for example from 40 to 48, yarn-ends in multiple upon a spool known as a "dresser spool", and in older practice, warps have been wound on section-beams in a similar way. These dresser spools may be from 30 to 40 inches long and have 10-inch heads, and when full, hold from 40 to 50 pounds of yarn. The filled dresser spool is in growing use as a commercial package for convenient transportation and sale of finished yarn. Customarily, such a parallel-wound spool is used by weavers in making up warps, the several yarns from a number of such spools, guided and separated by a comb or reed, being simultaneously wound onto a warp beam for use in a loom. This can be done conveniently, but when it is desirable, as often occurs, first to inspect and remove defects from the yarns, to use some of the yarns from the dresser spool singly, as for example when a warp is to be laid for striped or fancy weaves, or when yarns packaged on such spool are to be employed as wefts, or are to be used by knitting machines, it is necessary first to unwind the dresser spool and to separate and individually rewind its separated yarns in order separately to place or use such yarns.
- When the yarns are to be wound into individual cheeses or skeins or other packages for such separate use, they should obviously be unwound from the dresser spool at substantially the same rate and under the same tension in order to prevent breaking or snarling, which can be done by individually driving the winding packages under proper conditions, but there is no certainty of attaining this result if the yarns are merely pulled off from a freely rotating unwinding spool. For example, if the pull upon the yarn is wholly relied upon to start the heavy dresser spool into motion, an undue and injurious strain is often imposed upon some or all of the yarns, and on some more than others, while the momentum of the dresser spool, after it attains operative speed, is such that unless some form of brake is applied, it tends

to overrun and tangle the yarns when the machine is stopped.

Principal objects of the present invention are to provide a method, and apparatus useful in its performance, for overcoming the difficulties of rewinding from parallel or multiple-wound packages such as dresser spools, section beams or warp beams permitting the yarns to be rewound individually or in groups; for keeping each yarn under a substantially uniform and predetermined tension; and to avoid subjecting the yarns to undue strain or danger of snarling or tangling during the rewinding operation.

In the accompanying drawings the invention is shown by way of example as applied to certain instances only of rewinding operations, by way of illustrating the generic method and examples of preferred apparatus. In the drawings;

Fig. 1 is a front elevation of a machine for cross, or traverse-winding cheeses or cops of yarn provided with devices useful in attaining the objects of the present invention;

Fig. 2 is a vertical section, partly in elevation, on the line 2—2 of Fig. 1;

Fig. 3 is a vertical section, partly in elevation, on the line 3—3 of Fig. 1;

Fig. 4 is a side elevation, partly in axial section, of the usual dresser spool of commerce;

Fig. 5 is a fragmentary plan view illustrating details of the tension controlling mechanism;

Fig. 6 is a fragmentary front elevation of a skein winder constructed and operating according to the invention;

Fig. 7 is an elevation from the right-hand side of Fig. 6;

Fig. 8 is a side elevation of a reinspecting winder constructed and operating according to the invention;

Fig. 9 is a detail elevation, partly in section, of one of the unwinding dresser spools of the device of Fig. 8;

Fig. 10 is a detail elevation of one of the receiving or winding spools or beams showing its driving roll and yarn traverse guide roll; and

Fig. 11 is an enlarged detail elevation of change-speed mechanism also illustrated in Fig. 8.

The method of winding will best be under-

- stood by concrete examples practiced by apparatus of familiar types modified in accordance with the invention, for example for re-winding individual yarns singly, or in multiples of only two or more, from the large multiple package; or for skeining singly, doubly or in triples; or rewinding, inspecting and piecing-in in a multiple yarn sheet or run itself rewound in multiple.
- 10 Referring now to Figs. 1 to 5, a well-known and typical winder for winding cross-wound cheeses 34 of single or double or triple yarns at constant but adjustable surface speed by driving contact of each winding package with a tractor roll 1 is illustrated in Figs. 1, 2 and 3. A winder of the Foster type, selected for illustration, comprises a series of aligned tractor rolls 1 for driving the winding cheeses 34, said rolls being concentric with a shaft 2 in turn driven by a main shaft 3, which receives its motion from a constant speed pulley 4, driven by a belt 5, all as best shown in Figs. 1 and 3. For the present purposes, the machine is provided with a supplementary frame 6 and a gear train 7, which is driven by a sprocket 8, and a chain 17 presently referred to, for the purpose of providing a positive drive for the unwinding yarn mass at a speed related to the speed of the main shaft 3.
- 20 The gear train 7 transmits motion from the sprocket 8 to the shaft 9, which extends lengthwise of the winder frame and which is journaled at intervals in frame members 10. These frame members are disposed in pairs (but one pair being illustrated) and are furnished with upright slots such as 10^a for the reception respectively of the opposite ends of the spindle 11 central in a dresser spool 12. The dresser spools may be of any usual form, comprising the shaft or spindle 11, or a hole for such a spindle, and the spaced heads 13 and 14 between which the yarn is wound under tension, the several yarns being in a series of laterally thin masses 15, usually cross-wound, and in close lateral contact. The weight of the dresser spool is supported by a tractor roll 16 fast on the shaft 9 between the frame members 10. This roll turns the dresser spool by contact with the general surface of the winding comprised of the several yarn masses 15.
- 30 The chain 17 for driving the sprocket wheel 8 and positively rotating the unwinding mass 15 receives its motion from a sprocket wheel 18 secured to the shaft 3, which is driven by pulley 4. A cone pulley 19 is also secured to the shaft 3 and transmits motion by means of a belt 20 to a cone pulley 21 mounted upon a countershaft 22. The winding tractor roll shaft 2 receives its motion from the countershaft 22 by means of a belt 22^a trained about pulleys upon the respective shafts. The speed of shaft 2 is adjustable in relation to that of shafts 3 and 9 by change of the position of belt 20.
- 40 The belt 20 may be shifted upon the cones 19 and 21 for varying the speed of countershaft 22 for this purpose by a sliding belt shifter 23, as usual, which may be actuated, Fig. 5, by a link 24 connected to a crank pin 25 carried by a toothed disk 26. This disk may be turned by means of a worm 27 actuated by a hand wheel 28.
- 50 Each of the several yarns from the dresser spool passes up through pig-tail guides 29 and 30, mounted upon rails 31 and 32 respectively, on its way to the winding yarn masses 34. These yarn masses are formed upon spindles 35 and are supported and driven by engagement with the tractor roll 1.
- 60 In operation, the dresser spool spindle is driven at a constant surface speed by contact with the unwinding tractor roll 16, while the individual yarns are wound upon their respective yarn masses by contact with the tractor rolls 1, at a speed set at a slightly greater rate than the unwinding speed by adjustment of the hand wheel 28. The surface speeds of the unwinding and winding yarn packages are thus so related as to maintain a constant and predetermined tension upon the yarns, which tension is measured by the increment or ratio of winding to unwinding speed.
- 70 Since the unwinding package is positively driven, the yarns are relieved from the excessive strain ordinarily imposed upon them when the machine is started, while the positive control of the unwinding package prevents overrunning, slackening, or tangling of the yarns when the winding mechanism is stopped.
- 80 Any desired number of unwinding spools may be arranged upon the shaft 9, in accordance with the length of the winder and the number of ends wound upon each unwinding spool.
- 90 Referring now to Figs. 6 and 7, the multiple or parallel-wound unwinding package may have its yarn individually re-wound in skeins by the application of the same principles.
- 100 Uneven tension exerted upon the unwinding yarn is particularly objectionable in the winding of skeins as the unequally stretched strands elastically recover in the released skein and tend to kink and tangle when the skeins are removed from the reel, thus making the subsequent unwinding of the skeins difficult.
- 110 Referring to the drawings a frame A may be provided with suitable bearings for a main shaft 42 upon which a skeining reel 43 is mounted. This shaft is provided with fast and loose pulleys 44, 45 respectively, driven at a substantially uniform speed by the usual belt, not shown.

The machine may be provided with pairs of supports or brackets 46, 47, of which but one pair is illustrated. Each of these brackets is furnished with a guide slot 48 for the reception of an end 11 of the spindle of an unwinding multiple wound yarn package, such as a dresser spool 13, 14, 15.

The weight of this spool is supported by a tractor roll 50 so disposed that the yarn mass 15 upon the spool contacts directly with its peripheral surface. The tractor roll 50 is mounted upon a shaft 49 parallel to the shaft 42 and turning in bearings in the frame members 46, 47 and in a bearing 11 at its out-board end. The shaft 49 is provided with a cone pulley 52 and the shaft 42 is provided with a complementary cone pulley 53. A belt 54 encircles the cone pulleys and transmits motion from the shaft 2 to the shaft 49. The position 20 of the belt 54 is controlled by a sliding belt shifter 55 adjustable by a hand wheel and screw 55^a.

The machine may be provided with the usual traverse rail 56 having the pig-tail or other guides 57 through which the yarn *y* passes on its way to the reel. The yarn is guided from the unwinding mass 15 to the guides 57 by other guides 58 carried by a stationary rail 59.

30 In operation, the spool 13, 14 and yarn mass 15 rests by gravity against the surface of the tractor roll 50. The drive belt when on the fast pulley 44 turns the reel 3 at substantially uniform speed, and drives the shaft 49 and tractor roll 50 at a related speed according to the position of belt 54. The position of the belt 54 is so adjusted that the surface speed of the unwinding mass spool is a little less than that of the reel, to maintain a slight and uniform tension upon the yarn between the dresser spool and the reel.

Referring now to Figs. 8 to 11, the reinspection of yarn is commonly accomplished by mounting one or more dresser spools in the inspecting spooler, drawing off yarns from the several spools to form a sheet or run before which the operator sits, and rewinding the yarns after inspection upon a dresser spool, section beams, or one or more warp beams.

55 The inspecting spooler must be adapted to be instantly and frequently stopped and started during the inspecting operation. In starting an added burden is put upon the yarns due to the inertia of the unwinding spool, while the momentum of the latter causes it to overrun when the machine stops, thus slackening the yarn tension and sometimes tangling the yarns.

60 This invention is adaptable to the re-inspecting operation, and may be practised with the aid of apparatus of the generic type of this machine. The end frame members B of a suitable spooler, Fig. 8, are each pro-

vided with a downwardly and forwardly inclined rail 62, and these rails are furnished respectively with journal openings for the reception of the opposite ends of two series 63, 64, of tractor roll shafts.

5 A bracket 65 is mounted upon each of the members 62 adjacent to each of the bearings for the shafts 63. Similar brackets 65 are also mounted on member 62 in association with the bearings for each of the shafts 64.

Each of the brackets 65 is provided with a guide slot 67, while the brackets 6 are furnished with similar guide slots 68. The slots 67 constitute guides to position the opposite ends 11 of the spindles of unwinding yarn mass 15 on dresser rolls 13, 14, such as above described. The slots 68 receive the opposite ends of the spindles 11 of similar winding dresser rolls for the winding yarn mass 15.

80 The slots 67 are open at the top and bottom so that the weight of the unwinding dresser rolls is permitted to rest upon the traction rolls 75 carried by the shafts 63 and disposed immediately below the respective dresser rolls. In the same manner the weight of the winding dresser rolls is borne by the tractor rolls 76 mounted on the shafts 64. By this arrangement, rotation of the tractor rolls is frictionally transmitted to the dresser rolls by contact with the surface of the thread mass.

95 Each of the shafts 63 is provided with a bevel gear 77 which meshes with a bevel gear 78 on a drive shaft 79. Likewise each shaft 64 is provided with a bevel gear 80 meshing with a gear 81 upon a drive shaft 82. A gear 83 is secured to the forward end of the drive shaft 82 and meshes with a gear upon the drive shaft *d* of the machine which is driven at substantially constant speed by means of a pulley *p* and belt, (not shown).

100 Suitable change-speed adjustment is provided between the drive for rolls 76 and the drive for rolls 75. The forward end of the shaft 79 may be furnished, for example, with a gear 84 which meshes with a gear 85 carried by a counter-shaft 86 mounted in a bracket 87. A cone pulley 88 is secured to the countershaft 86 and a complementary cone pulley 89 is mounted on the rear end of the shaft 82. A belt 89^a is interposed between the cone pulleys 88 and 89 and transmits movement from the latter to the former. This belt may be shifted to vary the speed of the pulley 88 relatively to the pulley 89 by means of a belt shifting fork 90 carried by a slide member 91. The position of the latter is determined by a screw threaded rod 92 actuated by a hand wheel 93.

110 Each of the brackets 66 is provided with a supplemental bracket 94 having a bearing for the shaft of a traverse guide roll 95, Figs. 8 and 10. These rolls have cam slots 95^a for distributing the yarn upon the winding dress-

er spool. Each bracket 94 is provided with a guide eye 96 through which the yarn passes on its way to the cam slots 35.

From the unwinding dresser spools the 5 yarn Y passes over guide rolls 97, 98 and 99 and then downwardly to form the vertical sheet 100 before which the operator is positioned. At the lower edge of this sheet the 10 yarns pass about guide roll 101, thence over guide rolls 102 and thence to the guide eyes 96.

Preferably the winding tractor rolls 76 are 15 slightly larger than the unwinding tractor rolls 75 so that when the transmission at 88, 89 is neutral a constant increment of tension, depending on the length between winding and unwinding masses, is exerted upon the yarn between said masses. Whether or not the tractor rolls are of different size, a variable 20 effect of tension may be obtained by adjusting the belt 89^a, since by this means the speed of the drive shaft 79 may be varied relatively to that of the drive shaft 82. In practice the relative speeds of these shafts is so determined 25 as to maintain a constant and predetermined tension upon the yarn, and the degree of tension may readily be varied in accordance with the type of yarn being wound and the impressed or original tension.

30 While the machine is particularly well adapted for winding and unwinding yarn from dresser spools, it is evident that it might also be employed for winding yarn off of and onto ordinary warp beams or other yarn packages, that the number of spools in operation at any time is immaterial, and that the machine may be designed to wind a greater or lesser number simultaneously, as may be desired. The drive connections and change 35 speed mechanism shown by way of example 40 may be replaced by other devices adapted to effect the result.

I claim:

1. That method of tensioning yarn while 45 winding it from one package to another which comprises positively driving both the winding and unwinding packages, the surface speed of the winding package being greater than that of the unwinding package.

50 2. That method of rewinding yarns from a mass wound in multiple to form individual packages which comprises positively rotating both the winding packages and the unwinding mass, the surface speed of the unwinding mass being less by a predetermined amount 55 than that of the winding packages.

3. That method of rewinding yarns from a package comprising a series of multiple-wound yarns, which comprises positively 60 driving the unwinding yarn package at a predetermined speed less than the speed of winding and such as to maintain each individual yarn under tension.

4. That method of controlling yarn while 65 winding it from one package to another

which comprises positively rotating both the winding and unwinding packages, the linear take up of yarn by the winding package being greater than the surface speed of the unwinding package, and laying the winding 70 yarn in traverse winding relation during said operation.

5. In combination with mechanism for traverse winding a yarn mass, means for supporting a yarn package to be unwound, and means for positively rotating said yarn package in timed relation to the operation of the winding mechanism at a speed to maintain the yarn between said package and mass under tension. 80

6. In combination with mechanism for winding a yarn mass and comprising a winding spindle, means for rotatably supporting a yarn package to be unwound, and driving connections for turning said yarn package at a rate to secure an effective surface speed for unwinding incrementally less than the rate of winding on said spindle. 85

7. In combination with yarn winding means, means for supporting a package of 90 yarn to be unwound, and means for rotating said package positively in relation to the effective speed of said winding means at such a speed as to maintain a predetermined tension upon the yarn from the package on its 95 way to the winding means.

8. In combination with mechanism for simultaneously winding a series of yarn masses, means for supporting an unwinding yarn package comprising a series of multiple-wound yarns, and means for rotating the yarn package at such a rate as to impose a constant tension of predetermined degree upon the yarns on their way to the several 100 yarn masses, the winding yarn packages together comprising the sole means for drawing 105 off the yarn from the unwinding package.

9. In combination with a winding machine having a variable speed element for 110 controlling the rate of rotation of the winding yarn mass, means for supporting and positively rotating an unwinding yarn mass at a substantially constant surface speed related to and less than the speed of winding on said yarn mass. 115

10. In combination with a winding mechanism having means for rotating a winding yarn mass, a supplementary frame having guides for positioning an unwinding yarn package, a tractor roll for supporting and driving said package, and positive connections between the winding mechanism and said tractor roll for rotating the latter at constant predetermined speed, and means for guiding yarns directly from the unwinding 120 to the winding package under tension solely 125 the effect of the respective winding and unwinding speeds.

11. In combination with a winding mechanism having means for supporting a series 130

- of winding yarn packages, common variable speed means for rotating said packages, a supplementary frame having guide slots for the spindle of a dresser spool, a tractor roll for supporting and driving such spool, and gear connections for transmitting movement from the winding mechanism to the tractor roll, and means for turning the latter at constant speed.
- 10 12. A machine for winding and unwinding yarn comprising means for supporting a carrier for multiple winding and an unwinding multiple-wound yarn mass, and means for positively rotating said carrier and said mass in timed relation effective to maintain the yarn between said carrier and said mass under a tension appropriate to the yarn being wound.
13. A machine for winding and unwinding yarn comprising a winding tractor roll and an unwinding tractor roll, guide means associated with each roll for positioning a wound mass of yarn to rest by gravity against the peripheral surface of the respective rolls, means for driving each tractor roll, and means for causing one of said driving means to drive the others at a different speed, and means for guiding yarn from one yarn mass to the other.
- 30 14. A spooler comprising a frame provided with means for positioning a winding dresser spool and an unwinding dresser spool, a tractor roll for turning each spool, a shaft for each roll, a driven gear on each shaft, a driving gear meshing with each driven gear, and means for turning the driving gears at relatively different speeds adapted to cause the speed of the tractor roll for winding to exceed that of the tractor roll for unwinding.
15. A winding and unwinding machine comprising means for positioning a plurality of winding yarn masses and a plurality of unwinding dresser spools, a tractor roll for supporting and driving each yarn mass and each spool, traverse guide means associated with each winding mass, means for guiding yarns from the unwinding spools to the traverse means, a common drive shaft for all of the winding tractor rolls and a second shaft for driving all of the unwinding tractor rolls, and means for transmitting motion from one of said shafts to the other constructed and arranged to permit driving the unwinding spools at a surface speed less than that of the winding spools.

Signed by me at Wilton, New Hampshire,
